UNITED STATES PATENT OFFICE.

JOSEPH F. MORAN, OF PARK RIDGE, NEW JERSEY.

CAN-OPENING MACHINE.

1,110,334.

Specification of Letters Patent. Patented Sept. 15, 1914.

Application filed October 8, 1909. Serial No. 521,766.

To all whom it may concern:

Be it known that I, JOSEPH F. MORAN, a citizen of the United States, residing at Park Ridge, in the county of Bergen and State of New Jersey, have invented certain new and useful Improvements in Can-Opening Machines, of which the following is a specification.

This invention relates to improvements in can opening machines and the object of my invention is to provide a simple, inexpensive and highly efficient device arranged to cut the head of a can at one stroke of a lever.

The mechanism for carrying out my invention comprises a can holder, a knife carrier in which the knife is at all times held and concealed so as not to injure the hands of a user adjusting a can therebeneath, means for adjusting the can, means for causing the knife to penetrate the can as it makes its cycle, and means for actuating the knife as the lever is moved in a vertical plane.

With the above and other objects in view my invention consists in the combination, arrangement, and details of construction shown in the accompanying drawings and then more particularly pointed out in the appended claims.

Similar reference characters designate similar parts throughout the respective views, wherein—

Figure 1 is a side elevation of my invention, Fig. 2 is a cross-sectional view of the knife depressing mechanism to be described, shown in detail, Fig. 3 is an exaggerated top plan of the can table, Fig. 4 is a cross-sectional view of the table and adjusting means therefor, Fig. 5 is a fragmental detail view partly in section of the rotary screw for actuating the can cutter, Fig. 6 is a fragmental detail view of the knife depressing mechanism showing the knife depressed to engage a can, Fig. 7 is a detail view in perspective of the screw cylinder and loose shaft engaged thereby and, Fig. 8 is a top plan view of the screw mechanism and frame therefor.

Reference being made to the drawings which are merely illustrative of my invention, 1 designates a suitable frame fastened to a suitable support, said frame formed with the outwardly-extending arms 2, 3 and 4 respectively designed to support the parts of my device. Fulcrumed upon a pivot 4' fixed upon the arm 4 is a lever 18

having a handle 18', said lever being movably connected to the vertical shaft 16 so as to rotatably lift and depress the same vertically, by any suitable means, such as the radius link 17 pivoted to lever 18 and to a block 27 in which may swivel shaft 16. The arm 2 is formed with a bifurcated portion 5, the free end of each offset of which is formed with a sleeve through which passes a vertical screw 6 upon which screws a hand wheel 7 disposed between the offsets of the arm 5, the screw 6 being of sufficient length to allow for the vertical adjustment of the can holding table. Said table is composed of a bottom or base 8 secured rigidly to the screw 6 and moving therewith, and mounted upon said base are the oppositely-arranged rack bars 9 and 10 with which the pawl members 11 are arranged to have engagement, each pawl member being secured upon a cam member 13, which cams are disposed at diametrically opposite points and are arranged to ride against studs 13 formed underneath dogs 12 and mounted upon the rectangular guiding blocks 42 working in elongated openings 43 formed in alinement upon the top of the table, said blocks being integral with said dogs and held against displacement in said openings 43 by any suitable means. The dogs 12 are of greater width than said openings and are arranged to slide over the top 44 of the table which is spaced from and suitably secured to the floor or base 8' by any suitable means such as posts 45. The forward end of each dog is formed with a can engaging part 46.

The cam members 13' carry their pawls at their ends, and are integrally or otherwise formed upon the inwardly or horizontally disposed flange 12' formed upon a ring 8 embracing in sliding relation the ring 47 formed upon the base 8' upon which the flange 12' rests, said flange being held against displacement by the top 44 of the table. Reference being had to Fig. 3 it will be seen that when the blocks 42 are disposed centrally of said openings, the cam members will engage the studs at central points and the pawls carried by said cam members will engage said racks also. The cam surfaces are so formed that when the wheel handle 15 formed around the ring 8 is revolved to move the cams the studs will simultaneously move toward or from the axis of the screw 6.

The vertical shaft 16 is disposed in the collar 48 formed upon the frame arm 4 and is formed integral with a cylinder 26 having the usual spiral grooves 25 formed thereupon so that they may be instrumental in causing the cylinder 26 to be rotated a complete revolution when the latter is moved relatively of the pin 24 fixed upon the bar 24', said cylinder being held normally with its bottom opposite said bar, which bar is secured at opposite ends to the upright posts 22 and 23 secured at their ends upon transverse bars 20 which at their ends are rigidly connected by the bolts 21. Said posts 15 and bars form a frame which rests upon the cam head 28 and is held rigidly in upright position, so that the pin 24 may at all times fit the spiral grooves 25, by means of the tie bolt nearest the frame 1 which passes through the enlargement 49 formed upon arm 3 which is arranged to support the horizontal cam head 28, the usual nuts being interposed so as to properly position said tie bolts.

25 Formed centrally in the screw-cylinder 26 is a polysided channel 50 in which is snugly fitted in telescoping relation an upright shaft 51, said shaft 51, as clearly shown in Fig. 5 is formed at its lower end with an 30 enlargement 52 rotatably resting upon the cam head 28. Said shaft 51 is polysided to correspond to the shape of the channel into which it fits so as to be rotated in unison with the screw cylinder, and it is formed 35 with a cylindrical part projecting centrally through the cam head 28 and carrying spaced apart therefrom the knife carrier 34 at its bottom. The cam way 29 is formed on the periphery of the member 28 prefer- 40 ably less than a quarter of its length and the edge of said cam is so formed that the roller 31 to be described held normally against the edge of said cam may easily ride thereagainst and thereby run onto the per- 45 phery of the member 28 proper, in which last-named portion it is shown in Fig. 6. Said roller 31 is rotatably mounted at the upper end of a member 31' having a spring-receiving bore, the screw-threaded end of 50 the knife member 32 screwing into the trans- 55 verse surface of said channel and being limited in its turning by the shoulder 53 formed upon said knife. The member 31' telescopes at the upper end of a socket member 37 hav- 60 ing its bottom 54 dovetailed into the mem- 65 ber 34, the dovetailed portion being elongated and normally protruding at 39 so as to be easily shifted and held in adjusted position, the member 37 being positioned near 69 the periphery of the member 34 and said last-named member will be of such a diameter relatively of the cam head 28 that when it is revolved the roller 31 may ride over the 75 periphery of the cam head. The channel 36 in member 37 is formed with a reduced part

terminating in a relatively narrower part which is in registration with a vertical recess 33 formed in member 34 into which the cutting surface of the knife is held by means of the spring 35 coiled around said knife and bearing at one end against shoulder 53 and at the other against the shoulders formed by the narrow opening in member 37. Springs 55 are secured to the ends of the dogs and to the top of the table respectively. 75

The can opener operates as follows: By means of the screw wheel 7 the user will raise the can table until the can is brought alongside of but at a slight distance apart from the knife carrier 34. To mount a can in position upon the top 44 of the table the hand wheel 15 will be revolved so as to advance the dogs 12 toward the center of the table. By moving said wheel the cams 13' will ride against the depending studs 13, which forming part of the blocks 42 will move them in their rectangular openings 43 thereby imparting motion to the dogs 12 and causing them to move forwardly or rearwardly. As the cams 13' move the pawls 11 will ride over the teeth of the rack bars 9 and 10. It will be understood that any suitable means may be employed to release the pawls so as to retract the dogs in removing the can clamped thereby, no such means being shown in the drawings, but the provision of the means is within the province of those skilled in the art. 90

The springs 55 are arranged to normally hold the dogs in engagement with the portion of narrowest width of the cams so that they will be put under tension when the cams are arranged to move them out of their normal position. To adjust the dogs so as to grip a can of any determinate width the 100 wheel will be moved clockwise whereby the dogs will be moved toward the center, and if the can resting at the center of the table is of appropriate size the dogs will close against it. If however, the can is of such a 110 size that it is necessary to retract the dogs 12 then the wheel 15 can operate as follows: Before placing the can on the table move said wheel clockwise until the cams ride clear of the dogs 12 and the pawls 11 ride clear of the racks 9 and 10 whereupon the springs 55 will recoil and restore the dogs to normal position. Continue to rotate the wheel 15 until the broadest edge of each cam is brought into engagement with the diametri- 115 cally opposite pin or stud and then each pin or stud will be moved inwardly toward its center against the tension of said springs to allow said cams to ride against it at all points of its length. As the cams are moved 120 farther when the hand wheel continues to rotate clockwise the dogs will gradually be advanced more and more and the can may then be placed on the center of the table and will then be positively gripped. When the 130

- can is thus gripped by the dogs 12 and is in the position clearly shown in Fig. 6 the can opening mechanism may be actuated. The user will take hold of the handle of the lever 18 and will forcibly move it downwardly whereby shaft 16 guided in the collar 48 will in turn move downwardly and in consequence the screw-cylinder 20 will obey its movement and will move against the stud or pin 24 fitted into the cam grooves 25. The lever will then be given a full stroke so that the top of cylinder 26 will move alongside the bar 24 and owing to the configuration of the cam grooves and the position of the pin 24 the screw cylinder will rotate as it moves downwardly and will complete one revolution. It will be seen that said cylinder will move in telescoping relation against the polysided upright shaft 51 and owing to the 20 channel 50 of said cylinder being polysided said shaft will rotate in common with said cylinder which will also make a complete revolution. As said shaft 51 rotates the knife carrier will obey its movement and 25 roller 31 operatively mounted thereupon will ride off the edge of the cam way 29 onto the periphery of the cam head 20, which head is stationary as aforesaid. When this shall have been done, the cutting edge of the knife 30 will have been caused to project through the opening 33 in the knife carrier and will penetrate the can and as said carrier completes its cycle of revolution, the knife will cut the head of the can sufficiently to enable it to be 35 bent back. When the roller 31 is depressed as it engages the head of the can way, the member 31 will move in the socket member 37 against the tension of the spring 35 thereby causing the knife 32 to advance against the head of the can to be cut. When the cutting shall have been effected the lever 18 will move upwardly to its upper normal position and as it is being restored the knife carrier will move to occupy its first-named 40 position, the roller 31 falling into the cam way 29 and engaging the edge thereof to lie adjacent the edge 30 of the cam head when the cylinder shall cease to rotate. This will have caused the spring 35 to gradually release 45 coil to lift the knife so as to hold it out of projecting position. It will be seen from the above construction that the operator can adjust the can against the knife carrier without the hazard of injuring his fingers by 50 means of any projecting surface of the knife since the latter is held concealed at all times until the lever is actuated. The knife carrier may or may not be in engagement with the can as it rotates.
- 60 Numerous modifications may be resorted to in practice without departing in principle from the invention disclosed.
- Having described my invention I claim and desire to secure by Letters Patent:—
- 65 1. A can opener comprising a member, a knife normally incased in said member, a rotatable member, means actuated by said rotatable member to cause said knife to penetrate a can and to move around it, and means for actuating said rotatable member. 70
2. In combination a frame, a can holder at one end thereof, a vertically-disposed shaft; a cross-piece fixedly mounted on the frame carrying a projecting pin, a sleeve fixed on said shaft formed with a spirally wound groove at the bottom of which the pin fits, means for moving said sleeve downwardly to rotate it, a carrier mounted on said shaft and rotated by said sleeve, an upright knife normally held in said carrier, 75 means for projecting said knife through said carrier as the latter rotates, and means for automatically retracting said knife. 80
3. A device of the kind described comprising a standard, a can holding device at the lower end thereof, a carrier having a vertical slot, a knife normally held in said slot, and having a spring engaged shank projecting above said carrier, a vertically disposed shaft upon which said carrier is 85 mounted, means for rotating said carrier, means actuated by said rotating carrier to depress said projecting shank, and a vertically-movable actuator for said first-named means. 90
4. In combination, a standard, a can holding device at the lower end thereof, a carrier having a vertical slot, a knife held in said slot and having a shank projecting above said carrier, a roller carried at the top of 100 said shank, a fixed annular member having a cam recess in which said roller moves, means for rotating said carrier, said knife being depressed after the roller is released from the recess, said released roller contacting with the bottom of said member to hold the knife depressed, a vertically moving actuator for said rotating means, and means for automatically retracting said knife. 105
5. In a device of the character described, 110 the combination of a rotatable carrier, a tubular member mounted therein having an upper enlarged bore, a non-rotatable member having a cam recess, a tubular plunger held at the upper end of said bore, an upper roller mounted on said plunger riding against the surface of the cam recess, said carrier formed with a vertical slot, said tubular member having an under bore registering with said slot, a knife normally disposed in said registering recesses and having a shank fitting the upper end of the plunger, and a spring coiled around said shank and disposed in said plunger and tubular member. 115 120
6. In combination, a standard, arms formed on said standard, an annular member fixed horizontally to an intermediate arm and having a peripheral cam recess, a polysided shaft having a boss resting on 130

15 said member and a polysided part projecting above said boss, and a part projecting through said member, a cross-piece having a pin, a sleeve having formed longitudinally thereon cam grooves into the bottom of which said pin projects, means mounted on one arm for supporting said cross piece, a collar formed on the upper arm, a shaft vertically guided in said collar and fixed on 20 the upper end of said sleeve, said sleeve formed with a polysided bore in which said first-named shaft will fit when said sleeve has been actuated, means engaging said vertical shaft to rotatably depress said sleeve 25 against the poly-sided shaft, a knife carrier supported by said polysided shaft below said member, a vertically-disposed knife mounted on said member and arranged to protrude therebelow, a roller on said knife 30 projecting into said cam recess and depressed when riding clear thereof, and means for restoring said knife to normal position.

7. In combination a vertical standard having three spaced apart horizontal arms, a vertically movable can holder mounted on the bottom arm, a relatively large member formed upon the intermediate arm, a polysided shaft resting on said member, a

frame composed of transverse bars connected by elongated bars intermediate 30 their ends and having an outwardly projecting pin, a collar formed upon the free end of said first-named arm, a sleeve having a polysided bore held in telescoping relation relatively to the first-named shaft, an integral shaft upon said sleeve projecting through said collar, a lever pivoted intermediate the ends of the upper arm and arranged to depress said last-named shaft, means for holding said last-named shaft in swiveling relation to said lever, said sleeve formed with spirally-wound grooves at the bottom of which said pin projects, a knife arranged to travel around the periphery of a can as the poly-sided shaft rotates, means for normally housing said knife, and means for projecting said knife from its housing to penetrate a can.

In testimony whereof I affix my signature, 50 in presence of two witnesses.

JOSEPH F. MORAN.
